Attorney.

UNITED STATES PATENT OFFICE.

HENRY GUSTON OLIVE, OF MORENCI, ARIZONA.

LEAF-TOBACCO PACKING-CASE.

1,271,932.

Specification of Letters Patent.

Patented July 9, 1918.

Application filed February 25, 1918. Serial No. 219,029.

To all whom it may concern:

Be it known that I, HENRY G. OLIVE, a citizen of the United States, residing at Morenci, in the county of Greenlee and State 5 of Arizona, have invented or discovered certain new and useful Improvements in Leaf-Tobacco Packing-Cases, of which the following is a specification, reference being had therein to the accompanying drawings.

10 This invention relates to an improvement in packing cases more particularly adapted for use in storing and transporting leaf tobacco, and has for its object to provide a packing case of this class which, while it 15 will effectively protect the tobacco from impurities of all kinds, may be readily taken apart so as to expose the packed tobacco to enable it to be sampled in the warehouse or elsewhere; or the case may be opened out 20 at any time when it may be desired to admit air to the tobacco in the process of curing or seasoning. To this end two sides of the improved case, which is of rectangular form, are hinged to the bottom thereof, so 25 that they may be turned down on their hinges, while the other two sides, when in position for use, are removably mounted on the bottom or base of the case, these removable sides, and also the hinged sides, being 30 held in position at their tops, when the case is closed, by the cover of the case, detachable devices or hooks being provided for attaching the removable sides to the bottom and the cover of the case when the case is 35 closed, all as will hereinafter more fully appear.

In the accompanying drawing Figure 1 is 35 an elevation of the improved packing case in closed position with its hinged sides 40 shown in down-turned or opened-out positions in dotted lines. Figs. 2 and 3 are vertical sectional views, at right angles to each other, of the improved case. Fig. 4 is a horizontal section on line 4-4, Fig. 1.

45 Referring to the drawing, 12 denotes the bottom or base of the case which has a central rectangular raised portion 12^a, and, at two sides thereof, grooves 13. Two opposite sides 14 are hinged at their lower ends to 50 the bottom or base 12, while the lower ends of the two other opposite sides 15 fit in the grooves 13 in the said bottom or base. The cover 16 is provided on its under side with a rectangular, downwardly projecting or 55 depending portion 16^a, and is also provided with grooves 17 adapted to receive the upper

ends of the sides 15, while the sides 14, when the case is closed, abut against the two opposite end portions, at right angles to said grooves, of the downwardly projecting portion 16^a, said sides 15 being preferably held in an upright position by depending projections or dowel pins 18 attached to the cover 16.

When the case is closed the cover 16 is 65 fastened to the removable sides 15 by hooks 19, and the said removable sides 15 are also connected with the bottom or base 12 by means of hooks 20, these hooks being connected to the cover and base respectively by 70 screw eyes 21 or the like, and being adapted to engage loops or staples 22 on the sides 15. The hinged sides 14 are preferably provided at their tops on their outer sides with supports which may be in the form of cleats 75 23 which, when the said sides are in the down turned positions denoted in dotted lines in Fig. 1, will rest on the floor and hold the said sides level to avoid straining the hinges of said sides, so that the latter may, if desired, be used as platforms to support packages of tobacco taken from other packing cases and temporarily exposed for inspection or the like, without any strain on the 80 hinges of the said sides.

The two opposite sides of the improved case will preferably be provided with handles 24 for convenience in handling the case, and the cover 16 may also be provided with a handle 25 by which the said cover may be 85 conveniently lifted or carried, if desired.

When it is desired to expose the leaf tobacco or other material packed in the improved case, for exhibiting or sampling the same, or for any other purpose, the hooks 90 19 securing the cover 16 to the sides 15 may be released from the staples 22 and the cover then lifted off. When the cover is removed the sides 14 will be free so that they may be turned down on their hinges to 95 the positions denoted in dotted lines in Fig. 1. The hooks 20, securing the sides 15 to the base, may then be detached from their staples 22, leaving said sides 15 free to be removed from their steadyng grooves 13 in 100 the bottom or base 12; thereby fully exposing, in the form of a large square package or block, the tobacco or other material which has been tightly packed in the case.

From the foregoing it will be understood 110 that the invention provides a convenient packing and storing case, for leaf tobacco

or other material, which is of such a construction that it may be quickly and readily taken apart for the purpose of exposing the contents thereof, without removing screws or nails, and may be readily and quickly closed, after having been opened, simply by folding up the two hinged sides, placing the two removable sides in proper position, adjusting the lid or cover to place and then 10 fastening the latter and the removable sides securely in place by the hooks hereinbefore referred to.

When the case is closed the hinged sides 14 abut against the raised portion 12^a of the 15 bottom or base and also against the depending portions 16^a of the cover or lid 16 and are thus steadied or braced at their bottoms and tops on their inner sides. The said hinged sides are also braced or steadied from 20 top to bottom by shoulders 15^a afforded by the rabbeted edges of the removable sides 15.

The improved case may, if desired, be provided with casters or rollers for convenience in moving it about in the warehouse, 25 as denoted by dotted lines in Fig. 1. If thus provided with casters or rollers the cleats 23 on the hinged sides 14 should be correspondingly thicker, as denoted by dotted lines, to hold the hinged sides level and prevent 30 strain on the hinges of the sides 14.

The invention is not to be understood as being limited to all of the details herein shown. For example, while the hooks and staples hereinbefore referred to form convenient means for detachably securing the bottom and cover of the case to the non-hinged sides 15 thereof, any other suitable or equivalent detachable fastening devices might be employed for this purpose. Also 40 instead of the dowel pins 18 for detachably connecting the cover with the cleats 23 secured to the tops of the hinged sides 14, for the purpose of holding said sides in closed positions when the cover is on, any other equivalent detachable securing devices might 45 be used for this purpose.

Having thus described my invention I claim and desire to secure by Letters Patent:

1. A rectangular packing case, for leaf 50 tobacco or the like, consisting of a bottom or base having a central rectangular raised part and grooves at two opposite sides of said raised part, two sides hinged to said bottom or base and abutting, when in closed 55 positions, against said central raised part, two other opposite sides, disposed at right angles to said hinged sides and fitting at their lower ends in said grooves, a cover provided at its under side with grooves receiving the upper ends of said last-named sides and having a central depending part 60 against which the upper ends of said hinged sides abut, said cover having depending projections engaging the tops of said hinged sides, and detachable fastening devices for securing all of said sides and said cover in place to form a closed case.

for securing all of said sides and said cover in place to form a closed case.

2. A rectangular packing case, for leaf tobacco or the like, consisting of a bottom or base having a central rectangular raised part and grooves at two opposite sides of said raised part, two sides hinged to said bottom or base and abutting, when in closed positions against said central raised part, said hinged sides being provided at their upper ends with cleats or supports to sustain them when in down-turned positions, two other opposite 75 sides disposed at right angles to said hinged sides and fitting at their lower ends in said grooves, a cover provided at its under side with grooves receiving the upper ends of said last-named sides and having a central 80 depending part against which the upper ends of said hinged sides abut, and detachable fastening devices for securing all of said sides and said cover in place to form 85 a closed case.

3. A rectangular packing case, for leaf tobacco or the like, consisting of a bottom or base having a central rectangular raised part and grooves at two opposite sides of said raised part, two sides hinged to said bottom or base and abutting, when in closed 90 positions, against said central raised part, two other opposite sides disposed at right angles to said hinged sides and fitting at their lower ends in said grooves, said sides having rabbeted edges affording shoulders to support the edges of said hinged sides, a cover provided at its under side with grooves receiving the upper ends of said last-named sides and having a central depending part 95 against which the upper ends of said hinged sides abut, and detachable fastening devices for securing all of said sides and said cover in place to form 100 a closed case.

4. A rectangular packing case, for leaf tobacco or the like, consisting of a bottom or base having a central rectangular raised part and grooves at two opposite sides of said raised part, two sides hinged to said bottom or base and abutting, when in closed 110 positions, against said central raised part, two other opposite sides disposed at right angles to said hinged sides and fitting at their lower ends in said grooves, a cover provided at its under side with grooves receiving the upper 115 ends of said last-named sides and having a central depending part against which the upper ends of said hinged sides abut, said cover having depending projections engaging the tops of said hinged sides, and detachable fastening devices for securing all of said sides and said cover in place to form 120 a closed case.

In testimony whereof I affix my signature.

HENRY GUSTON OLIVE.
